UNITED STATES PATENT OFFICE.

ASHLEY C. BENNETT, OF MINNEAPOLIS, MINNESOTA.

CARBURETER.

1,103,930.

Specification of Letters Patent. Patented July 21, 1914.

Application filed July 1, 1912. Serial No. 706,908.

To all whom it may concern:

Be it known that I, ASHLEY C. BENNETT, a citizen of the United States, residing at Minneapolis, in the county of Hennepin and State of Minnesota, have invented certain new and useful Improvements in Carbureters, of which the following is a specification.

My invention relates to carbureters, and has for its object to provide a special type of closure for the valve or inlet port for the air supply, such that the degree of opening of said inlet port will be automatically varied to the speed of the engine and consequent rate of flow of air through the carbureter, while at the same time the oil level in the oil chamber of the carbureter receptacle will be kept at a constant level.

The full objects and advantages of my invention will appear in connection with the detailed description thereof and are particularly pointed out in the claims.

The figure of the drawing, illustrating the application of my invention in one form, consists primarily of a section through a carbureter having my invention applied thereto.

As shown in the drawings, a casing 1 incloses a chamber 2 for receiving the gasoline or other fuel oil through an aperture 3 in a plug 4 screwed into the casing 1 and in combination with the needle 5 comprising a needle valve mechanism of well known construction, the plug 4 having screwed thereon a cap 6 which forms a union with an elbow 7 having connection with a source of fuel supply, not shown.

The bottom of the casing 2 may, if desired, be closed by a cap 8 for permitting ready access to and the assembling of parts within chamber 2. The casing 1 is provided with a transverse partition 9 which separates the oil chamber 2 from an air and mixing chamber 10. The chamber 10 is connected by a passage 11 to a pipe 12 which, by connections not shown, leads to the cylinder of the engine, the opening in said pipe being regulated by a throttle valve 13 of usual construction. An air inlet pipe 14 opens through a port 15 into mixing chamber 10, said port having formed on the lower side thereof a valve seat 16 against which is adapted to seat the disk 17 of a check valve, the stem 18 of which passes through a guiding aperture 19 in partition 9 into the oil chamber 2.

The needle 5 has connected thereto by a ball and socket joint 20 an arm 21 which is pivoted at 22, and an arm 23 integrally connected with arm 21 extends in the opposite direction from pivot 22 and has a yoke 24 on the end thereof embracing the stem 18. A float 25 rides upon the liquid in the chamber 2 which has a fixed level, as indicated at 26. This float is provided with an aperture 27 which loosely surrounds the stem 18, the upper part of the float engaging the yoke 24 so that when the gasoline or other liquid fuel in the container rises to the level 26 the float 25 will operate to close the needle valve, but as the level of said liquid is caused to fall by use thereof the valve will be opened so that fresh supplies are admitted and the level within chamber 2 is kept practically constant.

The stem 18 extends centrally through a float 28 which may consist of cork or some other buoyant material, or be a hollow metal container, so long as its buoyancy will be of such degree at all times as to maintain the disk 17 in engagement with the valve seat 16 with a predetermined pressure which shall be just sufficient to keep the port 15 closed to the extent required to regulate the influx of air to the draft or speed of the engine. The float 28 may be cylindrical in cross section if chamber 2 is cylindrical, as is usually the case, in which event a sufficient passage-way 29 will be left so that as float 28 rises and falls within chamber 2 there will be plenty of room for the passage of liquid around the float from the upper to the lower part of the chamber and vice versa, with sufficient rapidity to prevent fluctuations of the liquid surface 26. To steady the float 28 a pin 30 may be secured centrally to the bottom cap extending up within chamber 2 and centrally within stem 18 positioned in float 28, which stem is preferably made hollow for that purpose. In case a hollow metal float is employed the stem will not need to extend through the body of the float but may be secured directly to the top, and the pin 30 will operate in a channel or way formed in the float. It is obvious that the same results of steady ing the float and permitting ready movement of liquid above and beneath the same may be effected by causing the float to engage or come close to the walls of chamber 2 and arranging a by-pass from the liquid either directly through or along the mar-

gins of the float or through a separate passage outside of chamber 2 in a well known manner.

In some instances it is desirable to have 5 a second air inlet port entirely open which is sufficiently large to admit enough air for the slowest engine speeds, and such a port is indicated at 31. The liquid fuel is 10 fed into the mixing chamber through an upright tube 32 connected by a passage 33 with chamber 2 and having a series of apertures 34 in the walls thereof through which the fuel is drawn by vacuum created by the draft of air through the mixing chamber, 15 the tension of this vacuum increasing in proportion to the increase in speed of the engine so that the liquid is drawn up farther in tube 32 and presented to an increasing number of said apertures to be fed at a 20 correspondingly increased rate in proportion to said degree of draft. The bottom tube 32 is surrounded by a cup 35 having the bottom thereof slightly below the level 26 of the fuel in chamber 2 so that a certain amount 25 of liquid will normally be exposed within this cup and excess of liquid drawn out through apertures 34 may pass back through said apertures positioned within the cup into the passage 33, all of these features being 30 shown and claimed in my Patent Number 927,211, dated July 6, 1909.

When used either with or without the extra air passage 31 it may sometimes happen that it will be desirable to vary the 35 closing pressure exerted upon valve disk 17. To effect this I may provide a socket 36 from the bottom of which projects a pin 37 engaging with disk 17, said pin having thereon a collar 38 slideable within the socket 40 36, a spring 39 surrounding the pin 37 and engaging the collar 38 so as to press the pin outward with a pressure which may be adjusted by means of a screw head 40 the face of which engages the upper end of 45 spring 39. By this means, when it is desired to use the carbureter under somewhat radically different conditions, the pressure of disk 17 upon valve seat 16 may be regulated as desired or even the disk 17 may be 50 held entirely out of engagement with valve seat 16 so as to leave a certain determined opening through the port 15. To prevent the suction of the air draft in chamber 11 operating to raise the level of liquid fuel in 55 chamber 2 a small air port 41 is formed in the wall of casing 1 at a point near the top of chamber 2 and above the fuel level 26.

In operation, when the engine is running at slow speed, if port 31 is employed most 60 or all of the air may be drawn through that port. If there is no second port the air will enter through port 15 pushing down the disk 17 and float 28. As the speed of the engine increases so that the feed of the air neces-

sarily must be increased the rush of air 65 through pipe 14 and port 15 will still further depress disk 17 until port 15 is opened to its fullest capacity. There will not, however, be quick fluctuations of the disk 17, as is the case where the valve member is 70 spring-controlled, since the inertia of the liquid which must be displaced and moved from the top to the bottom of float 28, or vice versa, as said float changes its position, will hold the valve disk 17 in constant position and prevent such fluctuation. It is noted that the float 28 is at all times submerged in the liquid of chamber 2. It cannot, therefore, operate to change the level 75 of said liquid. As herein shown, the float 80 is submerged in the liquid which comprises the fuel of the engine. It is obvious, however, and falls within the scope of my invention, that the float 28 might be positioned in a chamber supported from the fuel chamber 85 of the carbureter in which some other liquid than that which comprises the fuel might be employed.

I claim:

1. A carbureter comprising a casing having 90 an air inlet port and a valve member for closing the same, said valve member including a stem, a receptacle for the liquid fuel formed in the casing and separated from the air chamber of the carbureter into which receptacle said stem projects, means for maintaining the liquid fuel at a constant level within the receptacle including a float sustained upon the surface of said liquid, said valve stem extending centrally through said 95 float, a second float beneath the first named float and submerged in the liquid to which the valve stem is connected for positioning the valve member.

2. A carbureter comprising a casing having 105 an air inlet port with a valve seat surrounding the same and a valve member engaging said valve seat for closing the port, means for yieldingly holding the valve member in engagement with the valve seat, a 110 sliding member engaging the valve member, a spring for actuating the sliding member to move the valve member against the force of its positioning means, and means to adjust the force exerted by said spring.

3. A carbureter comprising a casing having 115 an air inlet port with a valve seat surrounding the same and a valve member engaging said valve seat for closing the port, means for yieldingly holding the valve member in 120 engagement with the valve seat, said casing being provided with a socket extending over the port into proximity with the valve member, a pin slideable in said socket and engaging the valve member, a spring in said socket 125 tending to force the pin outwardly, and means to vary the tension of the spring.

4. A carbureter comprising a casing hav-

ing an air inlet port surrounded by a valve seat and a valve member for engaging said seat to close the port, a receptacle partially filled with liquid, a float submerged in said liquid for connection with the valve member for holding the same in contact with the valve seat at a predetermined pressure, and yielding means engaging the valve member and tending to move the same out of engage-

ment with the seat against the force exerted 10 by the float.

In testimony whereof I affix my signature in the presence of two witnesses.
